FLUID COOLED WALL

Ivar L. Langvand, Barberton, Ohio, assignor to The Babcock & Wilcox Company, Rockleigh, N. J., a corporation of New Jersey

Original application March 12, 1946, Serial No. 653,843, now Patent No. 2,633,831, dated April 7, 1953. Divided and this application April 3, 1953, Serial No. 346,592

4 Claims. (Cl. 122—235)

The present invention relates to a fluid cooled wall of a type suitable for use in fluid heating apparatus wherein, for example, the wall forms a boundary of a combustion chamber or other hot-gas-containing space. Such a wall is suitably formed with fluid conducting tubes arranged in close succession therealong so as to afford a large available area of heat absorption surface for a given area of interior furnace wall surface. Openings are provided between tubes in the wall so as to permit access to the interior of the chamber for purposes of inspection or for the insertion of tools for removing slag or other accumulations from surface areas within the chamber. For each of such openings a novel form of closure means is provided, suitably in the form of a door having its supporting structure in heat transfer engagement with tubes adjoining the wall opening.

The present application is a division of my copending application Serial No. 653,843, filed March 12, 1946, now Patent No. 2,633,831.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which a specific embodiment of the invention is illustrated and described.

Of the drawings:

Fig. 1 is a fragmentary horizontal section of a furnace wall embodiment of the invention;

Fig. 2 is a sectional side view related to Fig. 1, taken along line 2—2;

Figs. 3 and 4 are fragmentary views related to Fig. 1, taken along lines 3—3 and 4—4 respectively showing certain wall tube formations;

Fig. 5 is a fragmentary plan view, similar to Fig. 1, showing a modified furnace wall construction; and

Fig. 6 is a projected side view of Fig. 5 showing elements included therein.

Figs. 1 and 2 show a furnace wall construction in which parallel tubes or tube lengths 11a are arranged in closely spaced contacting relationship along the inner side or face of an outer boundary wall 11. Openings are formed between tubes of the row, for inspection or lancing, for example, suitably by bending portions of tubes adjacent the locations at which such openings or ports are to be provided. The construction also includes suitable closures for such openings.

In detail, and referring first to Figs. 1—4, a lance door construction is shown in conjunction with contacting parallel tubes 11a arranged upright and associated with an outer wall 11 of a combustion chamber, the same general construction being applicable to other locations in the same wall or in other walls of similar formation. A wall tube 131 has a portion of its length bent outwardly from the row of tubes 11a, as shown at 132 in Fig. 3, in a plane oblique to the plane of the row at an angle of from 55 to 60 degrees, for example, to provide the desired extent of

wall opening 134. An adjoining tube 135 is similarly bent, although to a lesser degree, to provide a straight length portion 136 displaced inwardly from the row, as shown in Fig. 2, in a plane normal to the plane of the row, thereby defining the extent of intertube space required to accommodate the obliquely positioned bent tube portion 132, the displaced portion 136 of tube 135 being maintained parallel to tubes 11a for a sufficient distance to clear the bends in tube 131. For wall tubes of three inches outside diameter, as in the present embodiment, each tube bend is made on a centerline radius of eighteen inches to provide both the outwardly displaced tube portion 132 and the inwardly displaced tube portion 136.

A plate 137 shaped as in Fig. 3 is welded to tube 131 along the curved plate edge 138 to substantially close the gap between the bent-out portion 132 of tube 131 and the bent-in portion 136 of tube 135, plate 137 having a straight inner edge 139 formed with slots 141 therein for resilient engagement with the straight length tube portion 136. Plates 142 are welded to tube 131, at the opposite side from plate 137, along the curved plate edges 143, to close the gap between tube bend 132 and tube 11a at the opposite side of opening 134 from tube 135, the plates 142 having horizontal edges 145 longitudinally separated along tube 131 a distance equal to the effective height of opening 134 as determined by the height of the door frame opening 146. Each plate 142 is formed with a slotted straight inner edge 147 for resilient engagement with the associated wall tube 11a.

The closure unit for wall opening 134 includes an inner door frame casting 149 formed with a longitudinal projection 150 having a curved recess surface 151 conforming to and bearing against a straight tube 11a at one side of the opening, the body portion of the frame having a curved recess surface 152 conforming to and bearing against the bent-out tube portion 132 at the opposite side of the opening. Inner frame 149 is secured to the wall by studs 153 and 154 extending through top and bottom flanges 156 and screwed into nuts 157 welded to wall tubes, each stud 153 extending through a flange portion 159 parallel to the tube row and engaging a nut welded to a tube 11a adjacent the opening, and each stud 154 extending through a flange portion 159 inclined to the tube row at about twenty degrees and engaging a nut welded to the displaced portion 136 of tube 135, the assembly including nuts 155 attached to the outer ends of the studs.

The outer frame 161 and horizontally swinging door 162 are of the type disclosed in U. S. Patent 2,383,032, J. Abernethy, dated August 21, 1945, the door 162 having a latch 163 rotatable in a vertical plane and engaging catch 164 on the frame. In the specific form herein disclosed, door 162 is fitted with an insulating plug 165 of unsymmetrical cross section extending a considerable distance into and substantially filling the door frame opening 146 to protect the adjoining walls and door from furnace heat, the plug 165 comprising a sheet metal retainer 167 filled with suitable heat insulating material 168. The inner and outer door frames 149 and 161 are secured together by cap screws 169 and 171 along opposite sides, screws 169 at one side extending into outer frame 161 through side flange 172 of inner frame 149, and screws 171 at the opposite side extending into the outer frame through a thicker inner frame portion. Inner frame 149 includes an integral lug 173 extending into the outer frame opening closely adjacent a side wall thereof throughout the height of the opening.

It will be noted that the centerline of door frame opening 146 is laterally offset from the centerline of wall opening 134 toward the side occupied by wall tube 11a thereby rendering the described assembly particularly useful for lancing operations along an adjacent combustion chamber

wall, not shown; for example, a wall at an angle to wall 11 toward the side occupied by tube 135.

Figs. 5 and 6 illustrate a modified construction wherein an inner door frame 149a is secured to straight tubes 11a at opposite sides of wall opening 134, thereby simplifying fabrication and assembly of the frame required. Tubes 131 and 135 have portions displaced from the row as before and similarly received in frame recesses 151 and 152. In this form, the flange portion 159a is in a plane with flange portion 158 parallel to the tube row, and studs 153 of equal lengths are inserted through holes 175 therein for securing the frame to straight tubes 11a at opposite sides of the wall opening, there being no attachment to the displaced portion 136 of tube 135. Cap screws 169 and 171 extend through holes 176 and 177 respectively for securing inner frame 149a to outer frame 161.

While in accordance with the provisions of the statutes I have illustrated and described herein specific forms of my invention now known to me those skilled in the art will understand that changes may be made in the form of the apparatus disclosed without departing from the spirit of the invention covered by my claims, and that certain features of my invention may sometimes be used to advantage without a corresponding use of other features.

What is claimed is:

1. In a furnace wall comprising a row of parallel substantially contacting tubes, means defining an opening in said wall comprising two adjoining tubes of said wall respectively having portions offset toward opposite sides of said row into positions at a single side of said opening, one of said two tubes having its offset portion bent toward the outer side of said row in a plane oblique to said row and the other of said two tubes having its offset portion bent toward the inner side of said row in a plane intersecting said first named plane, a door frame disposed at the outer side of said row and providing communication with said wall opening, said frame having a wall portion at one side of said opening engaging the outwardly offset portion of said one tube and having an opposing wall portion engaging a separate tube of said row at the opposite side of said opening, means securing said door frame to wall tubes disposed at opposite sides of said opening, said securing means including a detachable connection extending from said frame to said separate wall tube, and a second detachable connection extending from said frame to a tube of said row other than said tube bent in said intersecting plane.

2. In combination, a furnace wall having contiguous fluid cooled tubes arranged in a row, means defining an opening in said wall comprising adjoining tubes of said row disposed on the same side of said opening, each of said adjoining tubes having an intermediate offset portion formed by bends the axes of which lie in substantially a single vertical plane, the vertical planes determined by

the axes of the offset portions of said adjoining tubes intersecting each other, a frame having an interior passage adapted to register with said opening and having portions thermally engaging portions of some of said fluid cooled tubes at opposite sides of said opening, said engaged tube portions including the offset portion of at least one of said adjoining tubes, said frame being secured to tubes at opposite sides of said opening, and a door for said opening mounted on said frame.

3. In combination, a furnace wall having contiguous fluid cooled tubes arranged in a row, means defining an opening in said wall comprising adjoining tubes of said row disposed on the same side of said opening, each of said adjoining tubes having an intermediate offset portion formed by bends the axes of which lie in substantially a single vertical plane, the vertical planes determined by the axes of the offset portions of said adjoining tubes intersecting each other at a point exteriorly of the furnace, a frame having an interior passage adapted to register with said opening and having portions thermally engaging portions of some of said fluid cooled tubes at opposite sides of said opening, said engaged tube portions including the offset portion of at least one of said adjoining tubes, said frame being secured to tubes at opposite sides of said opening; and a door for said opening mounted on said frame and having a plug of heat insulating material arranged to project into said passage when the door is in its closed position.

4. In combination, a furnace wall having contiguous fluid cooled tubes arranged in a row, means defining an opening in said wall comprising adjoining tubes of said row disposed on the same side of said opening, each of said adjoining tubes having an intermediate offset portion formed by bends the axes of which lie in substantially a single vertical plane, the vertical planes determined by the axes of the offset portions of said adjoining tubes intersecting each other at a point exteriorly of the furnace, a frame having an interior passage adapted to register with said opening and having portions thermally engaging portions of some of said fluid cooled tubes at opposite sides of said opening, said engaged tube portions including the offset portion of at least one of said adjoining tubes, said frame being secured to tubes at opposite sides of said opening other than said adjoining tubes, and a door for said opening mounted on said frame and having a plug of heat insulating material arranged to project into said passage when the door is in its closed position.
